E. D. JOHNSON.

TELEPHONE REPEATER CIRCUITS.
APPLICATION FILED JAN. 4, 1918.

Patented Dec. 30, 1919.

UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-REPEATER CIRCUITS.

1,326,199.

Specification of Letters Patent. Patented Dec. 30, 1919.

Application filed January 4, 1918. Serial No. 210,284.

To all whom it may concern:

Be it known that I, EDGAR D. JOHNSON, a citizen of the United States, residing at East Orange, in the county of Essex, State 5 of New Jersey, have invented certain new and useful Improvements in Telephone-Repeater Circuits, of which the following is a full, clear, concise, and exact description.

The invention relates to telephone repeater 10 circuits in which a repeater is variably connected between two telephone lines to provide for the two-way transmission of signals.

An object of the invention is to provide 15 means for automatically connecting the telephone repeater properly in response to voice currents impressed on the telephone line, whereby the two-way transmission of signals is made possible.

20 This is accomplished by means of a single repeating unit, the input side of which is normally connected to both telephone lines. A voice relay is provided for each line, the voice relay associated with the line carrying 25 the incoming signals automatically responding to the voice currents, to disconnect the input side of the repeater from the outgoing line and to connect the output side of the repeater to the outgoing line. The other 30 voice relay effects a similar change in the connections of the repeater for voice currents originating in the other line. In order to make sure that the proper voice relay will be operated, the input side of the repeater is 35 given a low impedance. Voice currents coming in over either line are shunted through the low impedance input side of the repeater, thereby operating the proper voice relay which is on the near side of the repeater, but 40 not operating the improper relay on the far side. The operation of either voice relay serves to render the other one inoperative, so that control of the repeater circuit connections is maintained by one voice relay or the 45 other.

The invention will be more specifically described in connection with the drawing which shows diagrammatically a repeater circuit provided with switching means 50 whereby the two-way transmission of signals is provided.

In the drawing the repeater 1 is connected between the two telephone lines 2 and 3. This repeater, while here shown as of the 55 mechanical type, may be of any other well-

known type. Between the repeater 1 and the line 2 is electromagnetic switch 4, the solenoid of which is normally energized through the circuit including the battery 5 and the armature 6 of the voice relay 7, the 60 circuit through the armature of vibrating contact 6 of the voice relay 7 being normally closed through its stationary contact 8. The switch 4 is provided with two armatures 9 and 10 which serve to normally connect the 65 line 2 to the input leads 11 and 12 of the repeater. The input side of the repeater, including the leads 11, 12 and solenoid 13, has an impedance which is low as compared to that of either line section, so as to effectively 70 stop the incoming voice currents at the repeater so that the voice relay at the near side of the repeater and not the one at the far side will be operated. In series with the line 2 and located between the armature 9 75 and the lead 11 is the solenoid of the voice relay 14. The voice relay 14 controls the vibrating contact 15 which, when the relay is deenergized, is in contact with its stationary switch 16. 80

The voice relays 7 and 14 are similar and when energized set their movable armatures into vibration, thereby interrupting the circuits in which their contacts are included. The invention is not restricted to any particular type of voice relay that may be employed, and by way of example it is indicated that these relays may be of the form shown in a patent to Brown 1,185,472, telephony, May 30, 1916. The contacts 15 and 85 16 of relay 14 are in series with the electromagnetic switch 17, similar to 4, in circuit with the solenoid of which is a battery 18. The contacts 15 and 16 being normally closed, the switch 17 is normally energized 90 and its armatures 19 and 20 assume the positions shown in the drawing, thereby connecting the line 3 to the incoming leads 11 and 12 of the repeater. The outgoing leads 21 and 22 of the repeater terminate in the 95 contacts 23 and 24 (of the switch 4) and 25 and 26 (of the switch 17). The outgoing side of the repeater is thus normally disconnected from both telephone lines, while its incoming leads are normally connected to 100 both.

If voice current originates in the line 2, the voice relay 14 is energized, thereby vibrating its contacts and deenergizing the switch 17, which releases its armatures 19 110

and 20, thereby disconnecting the incoming leads 11 and 12 of the repeater from the telephone line 3 and connecting the outgoing leads 21 and 22 to this line. When the 5 armatures of the switch 17 are thus in their alternate positions, the armatures of the switch 4 being in the position shown, the repeater is properly connected for repeating signals from line 2 to line 3. As long as 10 currents are impressed on the line 2, the voice relay 14 maintains the control of the connection without interference from the other voice relay 7, the latter having been rendered inoperative by having the circuit 15 through its solenoid opened when the armature 20 moved from its normal position. When those currents are no longer impressed on the line 2, the contacts 15 and 16 assume their normal closed position, thereby energizing the switch 17 and again connecting the incoming side of the repeater to both lines and disconnecting its outgoing side from both lines.

When voice currents originate in the line 25 3 the voice relay 7 vibrates its contacts to deenergize the switch 4, thereby disconnecting the incoming leads 11 and 12 from the line 2 and connecting the outgoing leads 21 and 22 of the repeater to the line 2. With 30 the armatures 9 and 10 in their alternate positions and the armatures 19 and 20 in the position shown in the drawing, the repeater is properly connected for repeating signals from the line 3 to the line 2. The 35 armature 9 in moving to its upper contact opens up the circuit through the voice relay 14, thereby rendering the same inoperative, the control being maintained by the voice relay 7 as long as signals are coming in 40 through the line 3.

While only a single embodiment of the invention has been shown, it is obvious that the invention is capable of expression in various other embodiments.

45 What is claimed is:

1. The combination of two lines, a repeater therebetween, said repeater having its input side normally connected to both of said lines, a switch comprising a solenoid 50 and an armature controlled thereby between said repeater and each of said lines, and a voice relay between each line and said repeater and adapted to control one of said switches.

55 2. A signaling system comprising two lines, a repeater therefor, said repeater having its input side normally connected to both and its output side normally disconnected from both of said lines, and means 60 responsive to voice currents to disconnect the input side of said repeater from one of said lines and to connect said last mentioned line to the output side of said repeater, said means comprising relays individual to said lines.

3. Two telephone lines, a repeater therefor, a switch between each line and said repeater, a solenoid for each of said switches, a voice relay in series with each of said lines, a vibratile contact for each of said relays, 70 each of said vibratile contacts being individual to one of said solenoids and with a source of current whereby said solenoids are normally energized.

4. The combination of two telephone lines, 75 a repeater having its input side normally connected to both of said lines, and switching means for disconnecting said input side from one of said lines and for connecting the output side of said repeater for transmission from one of said lines to the other, said means comprising voice relays having armatures individual to said lines.

5. The combination of two lines, a repeater having its input side normally connected to both of said lines, a relay and two armatures controlled thereby between each of said lines and said repeater, each side of said line being connected to one of said armatures, and means responsive to voice 90 currents to switch said repeater, whereby the two-way transmission of current is made possible.

6. The combination of two telephone lines, 95 a repeater therefor, switching means between said repeater and each of said lines, and a voice relay in series with each of said lines and individual to said switching means.

7. The combination of two lines and a 100 repeater therebetween having its input side connected across said lines, said input circuit having an impedance which is low as compared to that of either of said lines, whereby current impressed on said lines is 105 effectively diverted into said input circuit.

8. The combination of two lines, a repeater therebetween having its input side connected across said lines, said input circuit having an impedance which is low as 110 compared to that of either of said lines whereby current impressed on said lines is effectively diverted into said input circuit, and means responsive to current impressed on said lines for rendering said repeater effective for two-way repeating.

9. The combination of two lines, a repeater therebetween having its input side connected across said lines, said input circuit having an impedance which is low as 120 compared to that of either of said lines whereby current impressed on said lines is effectively diverted into said input circuit, and means responsive to said current impressed on said lines for reversing the connections of said repeater between said lines.

In witness whereof, I hereunto subscribe my name this 29th day of December, A. D. 1917.

EDGAR D. JOHNSON.
